UNITED STATES PATENT OFFICE.

EDWARD T. ROBINSON, OF ST. LOUIS, MISSOURI.

WINDOW-SASH HANDLE.

1,185,132.

Specification of Letters Patent.

Patented May 30, 1916.

Application filed January 28, 1915. Serial No. 4,844.

To all whom it may concern:

Be it known that I, EDWARD T. ROBINSON, a citizen of the United States of America, a resident of the city of St. Louis, State of Missouri, have invented certain new and useful Improvements in Window-Sash Handles, of which the following is a full, clear, and exact description, reference being had to the accompanying drawings, forming a part of this specification.

My invention relates to improvements in window attachments, and has for its object the production of a simple and inexpensive hand grip device adapted to be used in raising and lowering the upper sash of a window.

The preferred form of my invention comprises a vertical grip rod arranged alongside of a stile of the upper sash and secured to said upper sash. The vertical grip rod is preferably provided with a series of hand grip devices, and a corner of the stile is preferably cut away at a point adjacent to the grip rod as will be hereinafter described.

Figure I is an inside view of a window equipped with my attachment. Fig. II is an enlarged vertical section taken on line II-II, Fig. I. Fig. III is an enlarged horizontal section taken approximately on the line III-III, Fig. I. Fig. IV is an enlarged horizontal section taken approximately on the line IV-IV, Fig. I.

A designates a window casing, B is a lower sash slidably fitted to said window casing, and C designates an upper sash slidably fitted to said casing. The upper sash is a rectangular frame consisting of stiles 1, a top rail 2, and a bottom rail 3. The lower sash comprises a top rail 4, stiles 5 and a bottom rail 6.

E designates vertical grip rods arranged alongside of the stiles 1 and having their upper ends arranged in socket members 7 secured to the top rail 2, the lower ends of said grip rods being arranged in socket members 7^a secured to the bottom rail 3 of the upper sash. Each grip rod is preferably provided with a series of hand grip enlargements 8, and a corner of each stile 1 is preferably cut away to produce a series of hand-receiving recesses 9. The beveled faces 10, produced by cutting away the stiles, are separated from the vertical grip rods so that a person's hand may be easily inserted between said beveled faces and the

grip rods. The grip rods are arranged within the frame of the upper sash where they will not in any way interfere with the movements of the sashes, and one or both of these rods may be readily grasped in raising and lowering the upper sash.

The vertical grip rods are preferably secured to the stiles 1 by means of brackets 12, each having an eye which surrounds a grip rod E and a flange which is secured to a stile 1 by means of screws 13. These brackets 12 are arranged in vertical rows, and each bracket is preferably provided with a perforation 14 for the reception of a bolt 15 carried by the lower sash. The bolt 15 carried by the lower sash. The bolt 15 have shown is slidably fitted to a bolt holder 16 near the upper left hand corner of the lower sash, and it may be inserted into any of the brackets 12 at the left side of the upper sash. It is an advantage to make the brackets 12 exactly alike and the brackets at the right hand side of the window are therefore provided with perforations 14 adapted to receive a latch bolt.

The sashes may be opened a slight distance and secured together by inserting the latch bolt 15 into one of the brackets 12 at the left side of Fig. I, and when both sashes are closed they may be fastened by inserting the latch bolt 15 into the socket member 7^a at the lower left hand corner of the upper sash. Each socket member 7^a is provided with a perforation 17 for the reception of a latch bolt.

The vertical grip rods are so constructed and arranged that they may be readily grasped in raising and lowering the upper sash. Both hands may be used in operating the upper sash, and owing to the location of the grip rods, the power is applied where it will be most effective. To avoid the necessity of altering the sash rails 3 and 4, the grip rods and their hand grip devices 8 are arranged directly above the sash rail 3, as shown in Fig. II, where they will not strike or overlap the rail 4.

I claim:

1. The combination with a window sash, of a vertical grip rod arranged alongside of a stile of said sash and secured to said sash, one corner of said stile being provided with a series of recesses and said vertical grip rod being located adjacent to said recesses and provided with a series of enlargements located at the lower ends of said recesses.

2. The combination with upper and lower

window sashes, of a fastening device secured to the lower sash, grip rod holding members secured at the top and bottom of the upper sash, and a grip rod arranged vertically in said holding members, the lower grip holding member being adapted to receive said fastening device when the sashes are closed.

3. The combination with upper and lower
10 window sashes, of a vertical hand grip rod,

a vertical row of brackets connecting said hand grip rod to the upper sash, and a slideable bolt carried by the lower sash and adapted to be moved into and out of engagement with said brackets.

EDWARD T. ROBINSON.

In the presence of—

A. J. McCUALEY,
E. K. CLARK.
